UNITED STATES PATENT OFFICE

2,611,480

COMBINATION CIGARETTE CASE AND
IMPLEMENT

Michael Lavanish, Cleveland, Ohio

Application September 20, 1948, Serial No. 50,080

5 Claims. (Cl. 206—38)

1

This invention comprises a novel combination cigarette case and implement, wherein the implement element comprises an integral element of the structure of the cigarette case.

An important object of my invention is to provide such a combination structure wherein a penknife or like implement is carried within the cigarette case in such a manner that the penknife or like implement occupies no additional space in the cigarette case.

Another object of my invention is to provide such a combination structure in which the penknife or like implement is concealed within the cigarette case even when the cigarette case is open, and remains so concealed as an element of the structure of the cigarette case until disassociated therefrom.

A further object of my invention is to provide such a combination structure in which the implement element forms an operative element of the cigarette case structure when associated therewith in a condition in which it is normally inoperative to perform its implement function.

In carrying my invention into practice I contemplate the provision of a cigarette case of largely conventional structure involving the provision of a holding member arranged interiorly of the cigarette case for normally holding the cigarettes in position within the case when the case is open. However, I construct the said holding device or member in two cooperative units or parts, one of which units or parts comprises a penknife or like implement, and the other of which units or parts comprises a sheath or case permanently attached to the cigarette case, adapted to cooperate with the blade element or portion of the implement to receive the same in closed, protected and concealed condition, while the remaining portion of the implement cooperates with the sheath unit to provide a unitary holding device for holding cigarettes in the case when the latter is open.

Other objects, advantages, and features of the invention will appear from the following detail description taken in conjunction with the accompanying drawings, in which:

Figure 1 is a perspective view showing a cigarette case in open condition and embodying my invention, this view showing the sheath and implement units in their cooperative relation to form the unitary cigarette holding device.

Figure 2 is a view similar to Figure 1, showing the blade element of the implement unit partially withdrawn from the sheath unit, illustrating the manner in which the implement unit is separated for use for its implement function.

Figure 3 is a sectional view taken through the cigarette case when in closed condition, a portion of the holding device being shown in section, and a portion thereof being shown in elevation.

Figure 4 is a view similar to Figure 1, but illustrating a modification of the invention.

I now refer to the accompanying drawing, and more particularly at this time to Figures 1, 2, and 3 thereof. The cigarette case there shown and generally designated by the numeral 1 comprises a receptacle portion 2 designed to receive a plurality of cigarettes 3, as shown. The cigarette case 1 also includes a cover member 4 hinged as at 5 to the receptacle member 2. Suitable catch and latch means designated 6 and 7 are provided, respectively, on the receptacle 2 and the cover member, the catch member 6 having a finger engaging element 6a operable to release the catch 6 from latched relation with the latch 7 when it is desired to open the cover of the cigarette case.

The hinge means 5 for hingedly connecting the cover 4 to the receptacle 2 comprises a hinge pin 8 and hinge portions 9 and 10 respectively associated with the cover 4 and receptacle 2 and pivotally cooperating with the hinge pin 8.

Hingedly connected to the pin 8 is a cigarette holding device generally designated by the numeral 11. This holding device 11 generally performs the usual function of cigarette holding devices similarly provided in cigarette cases of conventional construction, this function being to engage the cigarettes 3 positioned in the receptacle 2 to hold the cigarettes therein when the cover 4 is open, as shown in Figures 1 and 2, to expose the cigarettes in the receptacle 2 to view for selection by the user. However, the holding device 11 is of novel construction in accordance with my invention, the same comprising two separable units consisting of an implement unit generally designated by the numeral 12, and a sheath unit generally designated by the numeral 13. The implement 12 comprises a blade element 14, such as a knife blade or the like, secured to a handle element 15. The sheath unit 13 is hinged to the hinge pin 8, and for this purpose the unit 13 is provided with hinge portions 16 pivotally cooperating with the hinge pin 8. The sheath unit 13 is hollow inside to provide an interior chamber 17 closed at the hinge end of the unit 13 and open at the end thereof designated 18, through which open end 18 the blade element 14 may be slidably inserted into the interior of the chamber 17 of the sheath unit 13. The interior chamber 17 of the sheath unit 13 substantially conforms to the major width and thickness dimensions of the blade element 14, so that the latter may be snugly and fixedly received within the chamber 17 by the sheath unit 13. In this connection it may be noted that the blade element 14 has its major width and thickness dimensions at the location designated 14a adjacent the handle portion 15 of the implement 12, the width of the blade element 14 at the location 14a being

substantially the same as the width of the chamber 17, and the thickness of the blade element 14 at the location 14a being substantially the same as the corresponding dimension of the chamber 17. Thus, when the blade element 14 is slidably inserted into the chamber 17 of the sheath unit 13, the interior walls of the chamber 17 snugly engage the portion 14a of the blade element 14. The frictional engagement of the inner walls of the chamber 17 with the blade element 14 inserted therein serves to maintain the two separable units 13 and 12 in firm association to provide a unitary cigarette holding device 11 in the relationship of the units 12 and 13 illustrated in Figure 1, the device 11 as a whole being hinged to the hinge pin 8.

The handle element 15 of the implement unit 12 is enlarged in relation to the dimensions of the blade element 14 so that the handle element 15 has substantially the same exterior dimensions as the sheath unit 13. The handle element 11 may thus serve as an abutment for abutting engagement with the end 18 of the sheath unit 13 for limiting the inward movement of the blade element inserted into the sheath unit 13 with the blade element inserted into the chamber 17 after the manner indicated in Figure 1. The making of the handle element 15 of exterior dimension corresponding with the exterior dimension of the sheath portion of the unit 13 makes the units 12 and 13 appear as a single integral structure when the said units are in their relationship illustrated by Figure 1.

A spring member 19 in the form of a coil spring encompasses the hinge pin 8 with one end of the spring 19 engaging the cover member 4 and the other end of the spring engaging the sheath unit 13 adjacent the hinge portion 16, whereby the cover 4 is biased to open condition upon release of the latch 7 from cooperation with the catch 6. The spring 19 also serves to bias the holding device 11 toward the receptacle 2 whereby the device 11 is resiliently or yieldably engaged with the cigarettes contained in the receptacle 2 to retain the cigarettes therein when the cigarette case 1 is in the open condition of Figures 1 and 2. The handle element 15 of the implement unit 12 is curved inwardly as indicated at 20, at the free end of the handle element 15, toward the interior of the receptacle 2 adjacent the catch 6.

In the use of my invention, the cigarettes 3 are normally retained in the receptacle 2 by engagement of the holding device 11 with the cigarettes, even when the cigarette case is in open condition of Figure 1. When it is desired to remove the cigarettes from the receptacle 2, the curved end 20 of the handle unit 15 may be engaged by the fingers of the user to lift up the device 11 against the action of the spring 19. When it is desired to employ the implement unit 12 in its function as an implement such as a knife or the like, the handle element 15 is engaged by the fingers of the user to pull it rightwardly, having reference to Figure 1 and 2, to withdraw the blade element 14 from the sheath unit 13 after the manner illustrated in Figure 2.

In the modification of Figure 4, the same device 11 comprising the implement unit 12 and the sheath unit 13 is utilized, but in addition, I have provided separate holding fingers 21 and 22 hinged to the hinge pin 8 and arranged to lie one on each side of the holding device 11 in parallel relation thereto and in yieldable engagement with the cigarettes 3 contained in the receptacle 2, the holding fingers 21 and 22 being biased by spring

means similar to spring means 19, not shown, for such yieldable engagement with the cigarettes 3, after the manner in which the device 11 is yieldably engaged therewith.

- 5 In the use of the construction of Figure 4, the holding means 21 and 22 and 11 are lifted up by finger engagement with the free ends thereof against the action of the spring means, for withdrawal of one of the cigarettes 3 from the receptacle 2. In the event that it is desired to utilize the implement unit 12 for its purpose or function as an implement, only the device 11 is lifted up by finger engagement with the free end 20, and then the implement 12 may be disassociated from the sheath unit 13 after the manner previously described, and under these conditions the cigarettes 3 continue to be retained in the receptacle 2 by engagement of the holding fingers 21 and 22 with the cigarettes.
- 10 20 It will be apparent that the exemplary constructions of my invention illustrated in the accompanying drawings are capable of various modifications within the purview of my invention, and I do not therefore wish to be limited as to 25 their construction except as contemplated within the scope of the appended claims.

Having thus described my invention, what I claim as new and desire to secure by Letters Patent of the United States is:

- 30 1. A combination cigarette case and implement comprising, in combination, a cigarette receptacle, and a cigarette holding device, positionable to engage and hold cigarettes in place in said receptacle, said holding device comprising a 35 sheath unit and an implement unit detachably cooperable with said sheath unit, and means movably connecting the holding device with the receptacle for positioning said device as aforesaid, said sheath unit and said implement unit 40 each having a portion engageable with cigarettes in said receptacle when said device is positioned as aforesaid.
2. A combination cigarette case and implement comprising, in combination, a cigarette receptacle, 45 a cover for the receptacle, and a cigarette holding device positionable to engage and hold cigarettes in place in said receptacle, said holding device comprising a sheath unit and an implement unit including a handle element and an 50 implement element connected thereto, said implement element being slidably insertable into said sheath unit for detachable cooperation of the sheath unit with the implement unit and for independent use of the implement unit when detached from the sheath unit, and means movably connecting said holding device with said receptacle for positioning said device as aforesaid, said sheath unit and said blade element each having a portion engageable with cigarettes in said 55 container when said device is positioned as aforesaid.
3. A combination cigarette case and implement comprising, in combination, a cigarette receptacle, a cover for the receptacle, and a cigarette holding device positionable to engage and hold cigarettes in place in said receptacle, said holding device comprising a sheath unit and an implement unit including a handle element and an 60 implement element connected thereto, said implement element being slidably insertable into said sheath unit for detachable cooperation of the sheath unit with the implement unit and for independent use of the implement unit when detached from the sheath unit, and hinge means 65 for hingedly connecting said cover and said implement element.
- 70

ceptacle, said sheath unit being connected with said hinge means for hinge movement of said device relative to said receptacle, said sheath unit and said blade element each having a portion engageable with cigarettes in said container when said device is positioned as aforesaid.

4. A combination cigarette case and implement comprising, in combination, a cigarette receptacle, a cover for the receptacle, and a cigarette holding device positionable to engage and hold cigarettes in place in said receptacle, said holding device comprising a sheath unit and an implement unit including a handle element and an implement element connected thereto, said implement element being slidably insertable into said sheath unit for detachable cooperation of the sheath unit with the implement unit and for independent use of the implement unit when detached from the sheath unit, and hinge means for hingedly connecting said cover and said receptacle, said sheath unit being connected with said hinge means for hinge movement of said device relative to said receptacle, and spring means cooperating with the sheath unit to yieldably urge said device into engagement with cigarettes contained in said receptacle, said sheath unit and said blade element each having a portion engageable with cigarettes in said container when said device is positioned as aforesaid.

5. A combination cigarette case and implement, comprising, in combination, a cigarette receptacle, a cigarette holding device comprising members, each having a portion adapted to engage cigarettes in said receptacle, one of said

members comprising a sheath unit, another of said members comprising an implement unit detachably cooperable therewith, and means movably connecting the holding device with the receptacle, combined with a cover for said receptacle, hinge means for hingably connecting said cover and receptacle, the sheath unit being associated with said hinge means for hinge movement of said device relative to said receptacle, 10 and a holding finger associated with said hinge means for hinge movement of said finger relative to said receptacle, said finger normally positioned in parallel relationship to said device for holding cigarettes from displacement when the 15 implement unit is displaced from the sheath unit.
